EXPANSIBLE LINK CHAIN FOR A BRACELET OR SIMILAR ARTICLE

Eugene Bazner, Providence, R. I., assignor to
Flex-Let Corporation, East Providence, R. I., a
corporation of Rhode Island

Application July 22, 1950, Serial No. 11,365

Term of patent 7 years

(Cl. D45—4)

To all whom it may concern:

Be it known that I, Eugene Bazner, a citizen of the United States, residing at Providence, in the county of Providence and State of Rhode Island, have invented a new, original, and ornamental Design for an Expansible Link Chain for a Bracelet or Similar Article, of which the following is a specification, reference being had to the accompanying drawing, forming part thereof.

Fig. 1 is a front view of an expansible link chain for a bracelet embodying my new design.

Fig. 2 is a side elevation thereof.

Fig. 3 is an enlarged perspective view of one of the top links, the bottom links being conventional in appearance.

I claim:

The ornamental design for an expansible link chain for a bracelet or similar article, as shown.

EUGENE BAZNER.
